ROLLING MILL

Jerome R. George, Worcester, Mass., assignor to
 Morgan Construction Company, Worcester,
 Mass., a corporation of Massachusetts

Application March 3, 1930, Serial No. 432,797

16 Claims. (Cl. 80—56)

The present invention relates in general to rolling mills, and more particularly to the maintenance of roll alignment therein.

In rolling mill practice, it is well recognized that especially bad effects, both on the rolled product and on the rolling apparatus, are produced when the axes of a pair of cooperating reducing rolls become crossed, in consequence of any lateral displacement of one or the other of said rolls from its normal operating position. In other words, it is of prime importance that the axis of each roll be at right angles to the direction of travel of the stock through said rolls; otherwise the stock may emerge from said rolls in a deformed condition, or with a tendency to twist, and furthermore, there will be stresses and strains of abnormal proportions set up in the rolling apparatus, particularly in an endwise direction, due to the powerful screwing action between the stock and the crossed rolls.

My invention resides in a combination and arrangement of parts whereby the rolls, in the event of their becoming crossed, or laterally displaced, are subjected automatically to forces which reestablish the parallelism of the roll axes. Other and further objects and advantages of the invention will be apparent from the following detailed description thereof, taken in connection with the accompanying drawings, in which—

Fig. 1 is a schematic view in side elevation, partly in section, showing my invention as applied to a stand of "backed-up" rolls.

Fig. 2 is a view showing the roll assembly in a plane at right angles to that of Fig. 1.

Fig. 3 is a detached view showing contact devices, at the ends of the working rolls, by means of which certain adjustment devices, as herein-after described, are made operative.

Fig. 4 is an enlarged detail view of the contact devices.

Fig. 5 is a wiring diagram.

Like reference characters refer to like parts in the different figures.

Referring first to Figs. 1 and 2, the invention is here shown as applied to a "backed up" rolling mill of conventional type, and consisting of a suitable housing 1, wherein are mounted a pair of cooperating working rolls 2, 3, which are engaged, respectively, by the backing-up rolls 4 and 5 of larger diameter. Such an arrangement is well known in the art, being shown and described, for example, in United States Letters Patent to McCleane, No. 104,177 of June 14, 1870; as described in the aforesaid patent, the plane containing the axes of the two working

rolls 2, 3 may be offset slightly, as shown in Fig. 1, from the plane containing the axes of the two backing-up rolls 4, 5,—such an arrangement having a stabilizing effect on the working rolls 2, 3, in that it substantially prevents, in one direction at least, their undue lateral displacement. As shown in Fig. 2, the working rolls 2, 3 may be driven in any suitable manner, as for example, by connecting them to the usual intermeshing driving pinions 6, 6, one of which is coupled to the shaft of a driving motor 7.

As best shown in Fig. 2, the backing-up rolls 4 and 5 preferably make their contact with the working rolls 2 and 3 respectively, by means of spaced collars 8, 8, so as to present an intermediate open space 9 in matching relation to the zone of the working rolls' contact with the stock *a*. The collars 8, 8 on the backing-up rolls 4 and 5 provide the necessary support and resistance to pressure to insure the proper operation of the working rolls 2 and 3; however, any scale which collects on the surfaces of said working rolls in their zones of contact with the stock *a* is not carried, by rotation of said rolls, into contact with the backing-up rolls 4 and 5, and hence the tendency of the working rolls to become pitted and roughened on account of said scale being ground into their surfaces is largely eliminated.

In the arrangement of apparatus herein illustrated, lateral displacement of the working rolls 2 and 3 in one direction,—to the left in Fig. 1, toward the bearing shoes 10, 10,—is substantially prevented because of the offset, above described, between the planes that contain, respectively, the working roll axes and the backing-up roll axes. In the other direction however, there is nothing to prevent such lateral displacement except the bearing shoes 11, 11 which engage the ends of each roll,—and it is apparent that only by constant and careful adjustment of these bearing shoes can the rolls 2 and 3 be kept in approximately correct alignment.

According to my invention, such adjustment, inwardly or outwardly, of the bearing shoes 11, 11 is adapted to be secured by the operation, in one direction or the other, of suitable motors, which are subject to separate manual control, whereby a condition of exact alignment of the roll axes may be readily established, as hereinafter described. Furthermore, according to my invention, these adjusting motors for the bearing shoes 11, 11 are each subject also to an automatic control, whereby, in the operation of the mill, if by wear of a bearing shoe or for any other reason, either end of a roll becomes displaced laterally, there is at

once automatically inaugurated an operation of the associated motor, to restore the roll to a condition of true axial alinement with the other roll.

5 As shown in Fig. 1, each bearing shoe 11 (there being two for each roll, one at either end) is movable in or out by a screw 12 which is turnable in the side of the housing 1 to produce lateral movement of the shoe. Each screw 12 is connected by suitable gearing 13 to a reversible driving motor 14, here shown as of the direct current type, said motor being operable, as hereinafter described, to move its associated bearing shoe inwardly or outwardly, as the case may be, for 10 the positioning and maintenance of the rolls 2 and 3 in correct axial alinement.

Referring now to Figs. 3 and 4, each end of each roll 2, 3 has disposed in operative relation to its periphery a contact shoe 15, the latter being 20 suitably mounted for limited pivotal movement on an arm 16 having a fixed pivot 17 in proximity to said shoe. The arm 16 is preferably of considerable length beyond the connection point of said shoe 15 thereto, in order to multiply, at its free 25 end, any movement imparted by lateral displacement of the associated roll 2 or 3. At its free end, each arm 16 carries an electrical contact member 18, yieldable thereon as indicated in Fig. 4, which is adapted to cooperate with a stationary electrical 30 contact 19 in the completion of an electrical circuit for operating, in the manner hereinafter described, one of the adjusting motors 14. Each contact 19, as shown in Fig. 4, is adjustably carried by a fixed bracket 20, and normally, in the 35 absence of lateral displacement of the associated working roll, there is a gap or space between said contacts 18 and 19. In the event of lateral displacement, such as to press an end of either working roll against one of the contact shoes 15, 40 the associated arm 16, in response to such pressure, will swing outwardly and engage its contact 18 with the stationary contact 19, this engagement being maintained by the yielding of contact 18 until the associated motor 14 has corrected the 45 lateral displacement of the working roll, whereupon the arm 16 will resume its normal position under the influence of gravity to separate the two contacts 18 and 19 and thereby stop the motor.

50 The wiring diagram of Fig. 5 illustrates the electrical connections by which the several motors 14, 14 are operated, both by manual and by automatic control, for the adjustment of the bearing shoes 11, 11 to establish correct axial alinement of the working rolls 2 and 3, and to correct said alinement whenever any lateral displacement of said working rolls occurs. As shown in said diagram, a suitable source of electrical supply, as indicated at 21, is made available, 55 through the closing of a switch 22, for the supply of current to four separate motor circuits 23, 23 connected in parallel to said supply 21. The several circuits 23, 23 are identical, and therefore a description of the same in connection with one 60 of said motors will suffice for all. As shown, each circuit 23 divides itself into two parts, one of which, as completed by the closing of a contactor or relay device 24, serving for the actuation of the associated motor in one direction, and the 65 other part, as completed by the closing of a contactor or relay device 25, serving for the actuation of the motor 14 in the opposite direction. The respective contactors or relays 24 and 70 25 are controlled, in the usual manner, by the energization of their associated coils or windings 75

26 and 27; one terminal of each of said windings is connected to one side of the supply 21, (here shown as the minus side), and the other terminal of each of said windings 26 and 27 is adapted, as hereinafter described, to be connected, selectively, 80 to the plus side of the line for the manual control of the adjusting motors 14, 14 in the following manner:—

As shown in Fig. 5, a switch 28, when thrown to the right, connects the plus side of the line in parallel with four individual switches 29, 29, each of which is shown in a neutral or inoperative position. When such a switch 29 is swung to the right (assuming the switch 28 to be in its right hand position), the coil or winding 26 is energized, thereby closing the contactor 24 and causing the flow of current to the motor 14 in such a direction as, in the present instance, will rotate its screw 12 outwardly, thereby retracting the bearing shoe 11 from the periphery of the associated working roll 2 or 3, as the case may be. On the other hand, when the switch 29 is thrown to the left, the coil 27 is energized, thereby closing the contactor 25 and causing current to flow to the motor 14 in the 100 other direction, whereby said motor's rotation is in such a direction as to rotate the screw 12 inwardly, thereby thrusting the bearing shoe against the working roll. In the neutral or central position of the switch 29, neither coil 26 105 or 27 is energized, and both contactors 24 and 25 remain open, so that no current flows to the motor 14. The above described mechanism and electrical connections constitutes a manually controlled means for the several motors 14, 14, 110 by which the initial setting of the rolls 2 and 3 in correct axial alinement may be readily secured,—the motors 14, 14 being operated to screw the bearing shoes 11, 11 at each end of each roll in or out as desired until the correct alinement 115 is established and the proper pressures of said shoes against said roll surfaces are set up. When this has been done, the apparatus is shifted over to automatic control in the following manner:—

120 Each adjustable contact 19 is first set in slightly spaced relation to its corresponding contact 18, such that any slight displacement at the end of the associated roll 2 or 3 will cause engagement of said contacts. The several switches 29, 29 125 being all then in their neutral or inoperative positions as shown, the switch 28 is swung from its right hand manual-control position into its left hand or automatic-control position, where it connects the plus side of the line, as shown, 130 in parallel with each of the four arms 16, 16. Each of the contactor coils or windings 27, 27, with one terminal thereof connected as above described to the minus side of the line, has its other terminal permanently connected, as 135 shown at 30, in Fig. 5, to one of the stationary contacts 19. Therefore, if any wear of a bearing shoe 11, or any undue pressure set up by the rolling operation, causes either end of either roll 2, 3 to be displaced laterally, toward the 140 right in Fig. 1, the resultant pressure of said roll end, on the adjacent shoe 15, procures an immediate engagement of the corresponding contacts 18 and 19, thereby completing the circuit through the particular coil or winding 27 145 to which those contacts are related. This closes the contactor or relay 25, causing the associated motor to run in such a direction as will rotate its screw 12 inwardly a sufficient amount to force the displaced roll end back to the nor- 150

mal position of correct axial alinement. Coincident with such restoration, the arm 16, which follows the roll back to normal position, carries the contact 18 away from the contact 19, there-
5 by deenergizing the coil 27 and opening the con-
tactor 25, whereupon the motor 14 ceases to
rotate.

Owing to the yielding of contact 18 on its
10 arm 16 when it engages the stationary contact
19, the circuit through the particular coil or
winding 27 to which the contact 19 is connected
is maintained an appreciable period long enough
to cause the associated motor to start and turn
its screw 12 far enough to return the displaced
15 roll to the position of correct axial alinement.
Obviously, the amount which the contact 18
yields, as well as the period of contact engage-
ment, is dependent upon the initial setting of
20 the adjustable stationary contact 19 with re-
spect to the contact 18 when the arm 16 is in
the position which it occupies with the associ-
ated roll in correct axial alinement, as shown
in Fig. 3. As a result, the device is adapted for
25 close adjustment to meet different operating
conditions of the rolling mill.

I claim,

1. In a rolling mill, a reducing roll having an
adjustable bearing, a reversible motor operable
30 to adjust said bearing in opposite directions, and
means responsive to deflection of the axis of said
roll from its normal right angle relation to the
direction of stock travel for procuring the oper-
ation of said motor, thereby to move said bearing
35 into a position where said right angle relation
is reestablished.

2. In a rolling mill, a reducing roll having an
adjustable bearing, a reversible motor operable
40 to adjust said bearing in opposite directions,
means responsive to deflection of the axis of said
roll from its normal right angle relation to the
direction of stock travel for procuring the oper-
ation of said motor, thereby to move said bearing
45 into a position where said right angle relation
is reestablished, said means being automatically
operable to discontinue the operation of said
motor upon the reestablishment of said right angle
relation.

3. In a rolling mill, a reducing roll, a normally-
50 inoperative contact device associated with said
roll and made operative when the axis of said roll
undergoes displacement from its normal right
angle relation to the direction of stock travel,
and means responsive to the operative condition
55 of said contact device for restoring the normal
position of said roll axis.

4. In a rolling mill, a reducing roll, an end
bearing for said roll, a normally-inoperative con-
60 tact device adjacent said bearing and made oper-
ative by the displacement of said roll from its
normal right angle relation to the direction of
stock travel, and means responsive to the opera-
tive condition of said contact device for shifting
65 said bearing to restore normal relation of said
roll.

5. In a rolling mill, a reducing roll, laterally
70 adjustable bearings for said roll, normally-in-
operative contact devices associated with said roll
near each end thereof, one or the other of said
devices being made operative when said roll
undergoes lateral displacement from its normal
75 position, and means responsive to such operative
condition of a contact device for laterally ad-
justing one of said bearings, thereby to restore
the normal position of said roll.

6. In a rolling mill, a reducing roll having a

laterally adjustable bearing, a reversible motor
for moving said bearing in or out, and means
responsive to lateral displacement of said roll
from its normal right angle relation to the direc-
80 tion of stock travel for procuring the operation
of said motor.

7. In a rolling mill, a pair of cooperating rolls
working normally with their axes in parallelism,
normally-inoperative contact devices associated
with said rolls and made operative by the cross-
ing of said axes, and means brought into action
by the operative condition of said contact devices
for restoring said rolls to a condition of axial
parallelism.

8. In a rolling mill, a reducing roll adapted
to operate normally with its axis at right angles
to the direction of stock travel, a motor normally
maintained inoperative, means set in action by
the displacement of said roll axis from said nor-
90 mal position for operating said motor, and means
for shifting the roll by said action of the motor,
until the roll axis resumes its normal position.

9. In a rolling mill, a pair of reducing rolls
adapted to operate with their axes in parallelism,
bearings for said rolls, a normally-inactive motor,
100 means responsive to the crossing of said axes for
initiating action of said motor, and means for
transmitting to a bearing of one of said rolls
the action of said motor, to restore the uncrossed
relation of said roll axes. 105

10. In a rolling mill, a reducing roll, a rever-
sible motor normally maintained inoperative,
means set in action, in one direction or the other,
by the displacement of said roll, in one direction
or the other, from its normal right angle relation
110 to the direction of stock travel for operating said
motor, and means for producing lateral motion
of said roll by said action of said motor, thereby
to restore said roll to its normal position.

11. In a rolling mill, a reducing roll, a member
115 associated with said roll and freely movable,
thereby when the axis of said roll undergoes dis-
placement from its normal right angle relation
to the direction of stock travel, and means auto-
matically responsive to said freely movable mem-
120 ber when actuated by the roll for forcibly re-
storing the normal position of said roll axis by
pressure exerted on the roll opposite to the direc-
tion of roll displacement.

12. In a rolling mill, a reducing roll, a member
125 near each end thereof, both of said members
being stationary when the roll axis occupies its
normal right angle relation to the direction of
stock travel, with one or the other of said mem-
bers being freely movable when displacement of
130 the roll axis from said right angle relation occurs,
and means automatically responsive to a freely
movable member when actuated by the roll for
forcibly restoring the normal position of said
roll axis. 135

13. In a rolling mill, a reducing roll, an end
bearing for said roll, a member adjacent said
140 bearing and freely movable by said roll when
the latter undergoes displacement from its nor-
mal right angle relation to the direction of stock
travel, and means responsive to said freely mov-
able member when actuated by the roll for auto-
matically shifting said bearing just enough to
restore said normal right angle relation of the
roll to stock travel.

14. In a rolling mill, a reducing roll, an end
bearing for said roll, a member adjacent said
145 bearing and freely movable by said roll when
the latter undergoes displacement from its nor-
mal right angle relation to the direction of stock
travel, and means responsive to said freely mov-

able member when actuated by the roll for shifting said bearing, said bearing shifting means being automatically rendered inoperative when the roll is restored to its normal right angle relation to stock travel.

15. In a rolling mill, a reducing roll adapted to operate normally with its axis at right angles to the direction of stock travel, power actuated means associated with said roll and normally maintained inoperative, and means set in action by the displacement of said roll axis from said normal position to automatically cause operation

of said power actuated means for shifting the roll until the roll axis resumes its normal position.

16. In a rolling mill, a pair of reducing rolls adapted to operate with their axes in parallelism, power actuated means associated with each roll and normally maintained inoperative, and means responsive to crossing of the roll axes to automatically set one of said power actuated means in operation for shifting one of said rolls and thereby restore the uncrossed relation of said roll axes. 80 85
